(57) **CLAIM**

The ornamental design for a computer generated image for a display panel or screen, as shown and described.

DESCRIPTION

FIG. 1 is a front view of a computer generated image for a display panel or screen showing our new design.

FIG. 2 is a front view of a second embodiment thereof; FIG. 3 is a front view of a third embodiment thereof; FIG. 4 is a front view of a fourth embodiment thereof; FIG. 5 is a front view of a fifth embodiment thereof; FIG. 6 is a front view of a sixth embodiment thereof; FIG. 7 is a front view of a seventh embodiment thereof; FIG. 8 is a front view of a eighth embodiment thereof; FIG. 9 is a front view of a ninth embodiment thereof; FIG. 10 is a front view of a tenth embodiment thereof; FIG. 11 is a front view of a eleventh embodiment thereof; FIG. 12 is a front view of a twelveth embodiment thereof; FIG. 13 is a front view of a thirteenth embodiment thereof; FIG. 14 is a front view of a fourteenth embodiment thereof; FIG. 15 is a front view of a fifteenth embodiment thereof; FIG. 16 is a front view of a sixteenth embodiment thereof; FIG. 17 is a front view of a seventeenth embodiment thereof; FIG. 18 is a front view of a eighteenth embodiment thereof; FIG. 19 is a front view of a nineteenth embodiment thereof; FIG. 20 is a front view of a twentieth embodiment thereof; FIG. 21 is a front view of a twenty-first embodiment thereof; FIG. 22 is a front view of a twenty-second embodiment thereof; FIG. 23 is a front view of a twenty-third embodiment thereof; FIG. 24 is a front view of a twenty-fourth embodiment thereof; FIG. 25 is a front view of a twenty-fifth embodiment thereof; FIG. 26 is a front view of a twenty-sixth embodiment thereof; FIG. 27 is a front view of a twenty-seventh embodiment thereof; FIG. 28 is a front view of a twenty-eighth embodiment thereof;

FIG. 29 is a front view of a twenty-ninth embodiment thereof;
FIG. 30 is a front view of a thirtieth embodiment thereof;
FIG. 31 is a front view of a thirty-first embodiment thereof;
FIG. 32 is a front view of a thirty-second embodiment thereof;
FIG. 33 is a front view of a thirty-third embodiment thereof;
FIG. 34 is a front view of a thirty-fourth embodiment thereof;
FIG. 35 is a front view of a thirty-fifth embodiment thereof;
FIG. 36 is a front view of a thirty-sixth embodiment thereof;
FIG. 37 is a front view of a thirty-seventh embodiment thereof;
FIG. 38 is a front view of a thirty-eighth embodiment thereof;

FIG. 39 is a front view of a thirty-ninth embodiment thereof;
FIG. 40 is a front view of a fortieth embodiment thereof;
FIG. 41 is a front view of a forty-first embodiment thereof;
FIG. 42 is a front view of a forty-second embodiment thereof;
FIG. 43 is a front view of a forty-third embodiment thereof;
FIG. 44 is a front view of a forty-fourth embodiment thereof;
FIG. 45 is a front view of a forty-fifth embodiment thereof;
and,
FIG. 46 is a front view of a forty-sixth embodiment thereof.
The broken line drawing of a display panel and screen in all views is for illustrative purpose only and forms no part of the claimed design.
